UNITED STATES PATENT OFFICE.

JOHN O. WINKS, OF SAN FRANCISCO, CALIFORNIA.

AUTOMATIC FIREARM.

1,104,947.

Specification of Letters Patent. Patented July 28, 1914.

Application filed March 3, 1913. Serial No. 751,679.

To all whom it may concern:

Be it known that I, JOHN O. WINKS, a citizen of the United States, and a resident of the city and county of San Francisco, 5 State of California, have invented certain new and useful Improvements in Automatic Firearms, of which the following is a specification.

The invention relates particularly to that 10 class of firearms in which the recoil due to the firing of a cartridge is utilized to extract the empty cartridge from the barrel and to insert another loaded cartridge.

One of the objects of the invention is to 15 provide an automatic firearm in which the cartridge is locked in the barrel at the time of firing.

Another object of the invention is to provide a novel means for conveying the cartridge 20 from the magazine to the barrel.

A further object of the invention is to provide an improved firing mechanism.

The invention possesses other advantageous features, which, with the foregoing, 25 will be set forth at length in the following description where I shall outline in full that form of the invention which I have selected for illustration in the drawings accompanying and forming part of the present specification.

The novelty of the invention will be included in the claims succeeding said description. From this it will be apparent that I do not limit myself to the showing made by said 25 drawings and description, as I may adopt many variations of my invention, as expressed in said claims.

In the drawings I have shown my invention as applied to a rifle, but it is evident 40 that the same structure with some modifications may be applied to shot guns and small arms.

Referring to said drawings: Figure 1 is a longitudinal vertical section taken through 45 the central part of the rifle, showing the various parts in position for firing. Fig. 2, is a similar view on a smaller scale, showing the position of the parts at the instant of firing. Fig. 3 is a view similar to Fig. 2, 50 showing the position of the parts after firing, with the breech bolt in its rear most position. Fig. 4 is a longitudinal vertical section of the magazine and receiver. Fig. 5 is a perspective view of the barrel removed 55 from the gun. Fig. 6 is a perspective view

of the breech bolt and cartridge lifting mechanism, part thereof being broken away. Fig. 7 is a perspective view from the rear of the breech bolt. Fig. 8 is a perspective view of the firing pin. Fig. 9 is a perspective view 60 of the lower part of the receiver and magazine holder. Fig. 10 is a longitudinal vertical sectional detail of the hand operative means for moving the cartridges within the receiver. Fig. 11 is a longitudinal vertical section of the receiver. Fig. 12 is a similar section of the receiver showing the opposite side. Fig. 13 is a perspective view of a clip arranged within the receiver for holding the cartridge next to be introduced into the 65 barrel. Fig. 14 is a top view of the trigger mechanism. Fig. 15 is a vertical section through the trigger mechanism. Fig. 16 is a perspective view of part of the magazine. Fig. 17 is a view of the stop for holding the 70 barrel in the receiver.

The firearm comprises a chambered casing or receiver 2 in which are arranged the various loading, firing and extracting mechanisms. The receiver is composed essentially 80 of two parts which are readily separable from each other so that the gun can be readily taken down. The top and sides of the receiver are formed integral and support the barrel 3 and the loading mechanism, and the bottom 4 is formed integral with part of the stock 5 in which the magazine 6 is arranged. The two parts are hinged or linked together at 7 and are latched at the rear end through the medium of the hook 8 and the spring 85 90 held pin 9.

The barrel 3 is provided on its rear end with an extension 12 which lies above the bore 13 and contacts with the top of the receiver. This extension terminates a short 95 distance in advance of the rear end of the receiver so that the barrel may have a limited reciprocating movement with respect to the receiver. This movement is limited in the forward direction by the stop 14, arranged in the front wall of the receiver, which is engaged by the lug 15 on the under side of the barrel. The rearward extension 12 of the barrel is of substantially the same width as the receiver and its movement is 100 guided thereby as it slides therein.

Arranged in the receiver 2 below the barrel extension 12 and contacting therewith is the breech bolt 16 which is provided at its forward end with an aperture 17 through 110

which projects the firing pin 18, which is arranged within the bolt 16. The bolt is locked in its forward position, locking the cartridge in the barrel, by means of the 5 latches 19 which are pivotally supported by the extension 12 adjacent its rear end. The front ends of these latches abut against the rear end of the bolt when the bolt is in the forward position, and being depressed at 10 the forward end, contact with the rear end of the bolt and lock it in the forward position. The latches are provided with projecting pins 21 which engage in inclined slots 22 in opposite sides of the receiver. 15 As the barrel is moved backward due to the recoil, the pins slide in the slots to the upper ends thereof and lift the latches 19 out of the path of the breech bolt 16, so that the breech bolt is free to travel backward to the 20 end of the receiver.

On the side of the breech bolt is a small dog 23, projecting beyond the front edge thereof, which engages a shoulder or recess on the cartridge and extracts it from the 25 barrel as the breech bolt moves backward. When the cartridge has been withdrawn from the barrel, the rear end thereof is engaged at one side by a finger 24 seated in a slot in one side of the receiver and the empty 30 cartridge is projected through the aperture 25 in the other wall of the receiver. For the purpose of allowing the insertion of the barrel extension provided with the projecting pins 21 into the receiver, the grooves 26 35 are provided, extending from the grooves or slots 22, forward to the end of the receiver. The breech bolt 16 is also provided with a groove 27 on that side opposite the dog 23, in which the head of the finger 24 slides as 40 the bolt reciprocates. Attached to and preferably formed integrally with the breech bolt 16 are two forwardly extending slides or arms 28 which extend into the tube 29 and are connected at their ends by the head 45 31. These slides 28 lie below the level of the breech bolt proper and the distance between the outer surfaces of the slides is preferably the same as the width of the bolt, which in turn is the same width as the extension 12 50 of the barrel.

Arranged between the slides 28 and secured to the head 31 is a bar 32 having a sloping or tapered end 33. Surrounding the bar 32 and lying between the slides 28 is a 55 coiled spring 34, which bears against the head 31 at one end, and contacts with the front of the receiver at the other end. The bottoms of the slides 28 are aligned with and bear upon the bottom 4 of the receiver, thereby guiding the breech bolt in its proper path. The bottom 4 is provided with a raised central portion 35 which forms grooves between itself and the sides of the receiver, in which the slides 28 slide. Arranged on this raised central portion 35 is a

plate 36 of the same width as the portion 35 which is loosely attached to the bottom 4 by means of the pin 37. On the plate 36 is arranged a spring clip 38 into which the cartridge is moved from the magazine and 70 from which it is raised and driven into the barrel.

The bar 32 is preferably of such length that the extreme end 33 thereof lies under the plate 36, as shown in Fig. 1. As the breech bolt is moved backward, due to the firing of the cartridge, the bar 32 is simultaneously moved backward, driving the wedge shaped end 33 thereof under the plate 36 and lifting the cartridge into such position that the return of the bolt will drive it into the barrel, which is widened at the rear end to facilitate the entrance of the cartridge. On the backward stroke of the breech bolt the coiled spring 34 is compressed, and the subsequent expansion of the spring moves the bolt back to firing position. Means have also been provided for removing the cartridge from the barrel without firing the same or for introducing a 90 cartridge into the barrel by manual operation. Surrounding the tube 29 at its outer end and slidably thereon is a grip 39 provided with a projection 41 extending through a slot 42 in the tube into the path of the head 31. As this grip is drawn backward by hand, the breech bolt and the bar 32 are moved back, opening the breech of the barrel and raising the cartridge on the plate 36 into position to be driven into the barrel. On the forward movement of the grip 39, the cartridge is driven into the barrel and the breech bolt locked in position.

Within the breech bolt 16 is arranged the firing pin 18 which is provided with a projecting point 43 which is adapted to project through an aperture 17 in the breech bolt and fire the cartridge. The breech bolt is formed hollow and the rear end thereof is partly closed by the slide 44, between which and the firing pin 18 is arranged a coiled spring 45, which drives the firing pin against the cartridge. The firing pin is provided with a rearwardly extending body 46 which projects backward beyond the end of the bolt and is provided on its rear end with a head 47 projecting below the body 46. The breech bolt is provided at opposite sides of its lower face with slots 48 which are aligned with the lower end of the head 47. Sliding in these slots 48 are the detents 49 of the trigger or releasing mechanism. These detents 49 are arranged in the rear of the position of the rear end of the breech bolt when it is in the forward position, so that as the breech bolt is moved forward, the detents engage the head 47 of the firing pin and cause the firing pin to remain stationary as the breech bolt moves to its forward position, thereby compressing the spring 45. 130

The firing pin releasing mechanism which is operated by the trigger 51 comprises a frame 52 which is provided at opposite sides with ears 53, by which it is pivotally attached at 54 to the upstanding ears 55 on the bottom 4 of the receiver. The two sides of the frame 52 are spaced apart a sufficient distance so that the cartridge may pass therebetween as it is moved out of the magazine. 10 A pressure on the trigger 51 moves the detents 49 allowing the firing pin to spring forward and fire the cartridge. The trigger mechanism is locked, when desirable, against accidental discharge by the slide 62 arranged 15 in the stock of the gun and provided with a button 56 projecting through said stock. When the slide 62 is moved to operative position it contacts with the cross piece 57 on frame 52 and prevents the frame from being 20 moved about its pivot.

The magazine 6, in which the cartridges are arranged, comprises a metallic shell 59 which is removably secured in the stock 5 of the gun and from which it may be readily 25 released and withdrawn when desirable. The magazine shell 59 is provided with a rounded upper face 66 corresponding to the curvature of the rear end of the cartridge and is of such width and inclination, that when the 30 cartridges are placed therein, the projectiles 67 contact with the forward face of the magazine below the point thereof, as shown in Fig. 1. By means of this arrangement the cartridges slide readily in the magazine and 35 do not become jammed therein. Arranged within the magazine shell is a follower 63 which is pressed forward by the coiled spring 64. The follower is designed so that it contacts with the cartridge at the lower 40 part of the rear end only, pressing the upper part of said rear end into engagement with the rounded upper side of the magazine. By exerting an upward pressure at the rear end of the cartridge only, and constructing 45 the magazine so that the point of the projectile does not contact with the magazine, the cartridges are readily advanced as the leading one is withdrawn. The upper or discharge end of the magazine is cut away 50 at the front portion and contracted at the top portion to allow the cartridges to be withdrawn longitudinally therefrom, and to prevent the spring 64 from forcing them out sidewise. Arranged on the bottom of 55 the breech bolt at the rear end thereof, is a dog 65 which on the forward movement of the bolt engages the leading cartridge in the magazine and moves it forward into the clip 38, from which the previous cartridge 60 has just been removed.

I claim:

1. In an automatic firearm, a barrel, a reciprocating breech bolt arranged behind said barrel, means arranged below the forward position of said bolt adapted to support a

cartridge and a wedge shaped member attached to said bolt adapted to raise said means as the bolt moves to its rear position.

2. In an automatic firearm, a barrel, a reciprocating breech bolt arranged behind said barrel, a plate arranged below the forward position of said bolt adapted to support a cartridge, and a wedge shaped member attached to said bolt adapted to be moved below said plate and raise the same as the bolt moves to its rear position. 75

3. In an automatic firearm, a receiver, a barrel attached to said receiver, a tube arranged below said barrel, a reciprocating breech bolt arranged behind said barrel, slides connected to said bolt and extending into said tube, a bar having a wedge shaped rear end attached to said slides at the forward end, and a cartridge supporting plate arranged in said receiver below the forward position of said bolt under which said wedge shaped end is adapted to engage. 80 85

4. In an automatic firearm, a receiver, barrel and magazine in combination with a tube arranged below and attached to said barrel, a reciprocating breech bolt arranged in said receiver behind said barrel, slides connected to said bolt and extending into said tube, a bar having a wedge shaped inner end attached to said slides, the lower face of said bar being alined with the bottom of the receiver, a plate arranged on the bottom of the receiver, a cartridge supporting means on said plate and a spring engaging said slides tending to hold the bolt in its 90 95 forward position. 100

5. In an automatic firearm, a barrel, magazine and receiver in combination with a reciprocating breech bolt arranged in said receiver behind said barrel, slides connected to said bolt and bearing against the bottom of the receiver, a cartridge holder arranged below the forward position of the breech bolt, means for moving a cartridge from the magazine into said holder on the forward 105 movement of the breech bolt, and a wedge shaped member attached to said slides adapted to raise the cartridge holder on the rearward movement of the bolt. 110

6. In an automatic firearm, a barrel, magazine and receiver in combination with a reciprocating breech bolt arranged in said receiver behind the barrel, slides connected to said bolt bearing against the bottom of the receiver and extending into a tube arranged below the barrel, the tube, means attached to said slides for raising the cartridge in the receiver into position to be driven into the barrel by the breech bolt, and a grip surrounding said tube adapted to 120 be reciprocated manually to reciprocate said slides. 125

7. In an automatic firearm, a hollow breech bolt provided on the lower edge of its side faces with grooves, a firing pin in 130

- said bolt provided at its rear end with a head arranged in line with said grooves and adapted in its normal position to close the rear ends of said grooves, detents arranged 5 in line with said grooves adapted to enter said grooves on the rearward motion of the bolt and to retain said firing pin on the forward movement of the bolt, a spring arranged between said firing pin and bolt 10 adapted to be compressed on the forward movement of the bolt, and means for moving said detents out of engagement with said head.
8. In an automatic firearm, a trigger 15 mechanism comprising a frame having side members spaced apart a distance greater than the diameter of the cartridge, a bar connecting said side members, and a slide adapted to be moved manually into contact 20 with said bar.
9. In an automatic firearm, a barrel, a reciprocating breech bolt arranged behind said barrel, means arranged below the forward position of said bolt for supporting a 25 cartridge, means for moving the cartridge into said support, and a wedge shaped member attached to said bolt adapted to raise said support as the bolt moves to its rear position.
10. In an automatic firearm, a receiver, barrel and magazine, in combination with a reciprocating breech bolt arranged in said receiver behind said barrel, means arranged below the forward position of said bolt for 30 supporting a cartridge, means operative on the forward movement of said bolt for moving a cartridge from the magazine to the supporting means, and a wedge shaped member attached to said bolt adapted to 35 raise said support as the bolt moves to its rear position.
11. In an automatic firearm, a receiver, a magazine arranged below and in the rear of said receiver adapted to hold cartridges 40
- in a horizontal position, a reciprocating breech bolt arranged in said receiver, means arranged below the forward position of said bolt for supporting a cartridge, means operative on the forward movement of said bolt for moving a cartridge from the magazine 45 to said supporting means and a wedge shaped member attached to said bolt adapted to raise said cartridge as the bolt moves to its rear position.
12. In an automatic firearm, a receiver, a magazine arranged at the rear end of said receiver adapted to hold cartridges in a horizontal position, a reciprocating breech bolt in said receiver, means arranged below the forward position of said bolt for supporting a cartridge horizontally, means operative on the forward movement of said bolt for moving a cartridge longitudinally from said magazine to said supporting 50 means and means operative by the backward movement of said bolt for raising said supporting means.
13. In an automatic firearm, a receiver, a stock, a magazine in said stock adapted to hold cartridges in a horizontal position with the upper cartridge in said receiver, a reciprocating breech bolt in said receiver, means arranged below the forward position of said bolt and in line with the upper cartridge for supporting a cartridge, means operative on the forward movement of the breech bolt for moving said upper cartridge 55 longitudinally to said supporting means, and means operative by the backward movement of the bolt for raising said supporting 60 means.
- In testimony whereof, I have hereunto set my hand at San Francisco, California, this 24th day of February, 1913.
- JOHN O. WINKS.
- In presence of—
H. G. PROST,
P. S. PIDWELL.
